TOP STRUCTURE FOR VEHICLES

Filed Oct. 23, 1929

UNITED STATES PATENT OFFICE

ALEXIS KELLNER, OF BERLIN, GERMANY

TOP STRUCTURE FOR VEHICLES

Application filed October 23, 1929, Serial No. 401,761, and in Germany January 11, 1929.

This invention relates to folding top structures for vehicles preferably for the called convertible type of motor car, the object being to produce a simple and efficient top structure which may be easily and rapidly raised when so desired.

One feature provides an efficient structure having a front portion to span the usual side exposures or windows. Said front portion is to constitute an essentially self-sustaining or cantilever construction very much desirable for instance in cases where said front portion is doubled up by means of hinges or the like. The cantilever construction will not require intermediate supporting means generally found to prevent sagging of said hinges or joints.

Another feature employs individual telescopic or encased spring members at each side to expedite the raising of said front portion, preferably in addition to other customary springs applied to the basic rear portion of the top, all to allow quick handling of the entire structure.

In the preferred embodiment of the invention the front portion extends with the aid of the associated novel spring-arrangement, while the telescopic members anchored upon the rear portion or main frame will reach their limit of expansion, so as to take over the function of a strut which will brace the said front portion.

Another feature provides means for easily lowering the top to inactive position.

Other features and advantages will herein-after appear.

In the accompanying drawings:

Fig. 1 shows a motor-car with the top structure in raised position.

Fig. 2 shows the initial operation when folding the top structure.

Fig. 3 shows the initial operation when raising the top structure.

Figs. 4 and 5 are parts sectional details of the telescope members showing the encased spring in two different states of expansion.

Fig. 6 shows a latch constituting a refinement of the construction.

The numeral 1 indicates the vehicle body upon which is mounted the novel folding top

structure. Swingably arranged on either side of the vehicle body are the main supporting members or columns 2, each having fastened to its lower end a rearwardly inclined arm 3 by means of which to be pivoted 55 at 4 upon the body. While in raised position the columns 2 may be secured by usual coach joints 5. The rear of the top covering is held in place by the well known swingable rear bows 6 and 7. Linked to each of the two 60 swingable columns 2 are the rear elements 8 of two cant rail members forming the front structure of the top, said elements 8 being connected through hinges 9 with the front elements 10 of said cant rail members. Moreover there are provided links 11 and 12 of a parallel link connection, said links 11 having extensions to terminate in the cross members 13 to support the top covering.

According to the invention there is provided a telescopic member or spring between each of the swingable columns 2 and the associated cant rail members. The telescope members or springs may include a tube member 14 pivoted upon the swingable column 2 70 and an associated plunger 15 to be pivoted upon the front element 10 of said cant rail members. Thread 16 is provided upon the front end of the tube member 14, upon which fits the nut or cap 17. With the top being in 75 full active position, the piston 18 fixed upon the plunger 15 will abut against the inside of cap 17, while now the spring element 19 proper is left practically without tension, all the conditions as just described being 80 explained more clearly hereinafter.

The function of a swingable member or latch 26 coupled with the hinge 9 between the elements 8 and 10 also is to be explained in 85 the following.

The front ledge of the top structure when in active position will rest upon columns 20. By virtue of its particular construction, the top structure needs no support at the joint between the elements 8 and 10, hence even with the top up, there is no need for usual window guides 21 and 22 to be turned up to form a support.

Usual spring means or a preferred tele-

scope springs 23 may also serve as an aid in raising the columns 2.

Tension upon the top structure is a suitable top covering 24 made up of fabric, leather or the like. A strap 25 allows the top structure to be pulled from its active to its folded position.

The mechanism is to be handled as follows:

10 In order to raise the top, first the front element 10 of the cant rail members as well as the members 11 and 12 of the parallel link connection are to be brought into the Figure 3 position, this operation being effectively aided by the telescope members 14 and 15. At 15 this point it should be noted that the telescope spring reaches a dead centre position before the top is completely folded, in other words there will be no tendency left to raise the front elements 10 after the folding.

20 After the top structure with the assistance of the telescope spring members 14, 15 has been brought into the Fig. 3 position, the rear top portion may be raised together with the column 2 by lifting the member 6. The 25 operation of raising this rear portion is assisted by the telescope spring member 23 in a manner known in the art. While raising the rear portion the front portion also reaches its extended position, the telescope spring member 14, 15 effectively causing the front part of the members 10 to rest upon the columns 20. This being accomplished, the telescope spring member 15, 14 takes the position as per Fig. 4. The spring 19 then has 30 no tension while the tube member 14 and the plunger 15 take the part of a strut preventing the members 8 and 10 from sagging through downwardly. The arrangement of this 35 strut does away with the centre support which normally is employed to carry the hinges 9 when the top is up. That is to say the window guides 21, 22 may remain in their lowered position even with the top 40 structure being raised. To adjust the length of the telescope members 14, 15 in their function as a strut, the nut 17 threaded upon said tube member 14 may be adjusted. The further the nut 17 proceeds upon the tube 45 member, the quicker the piston 18 will abut against nut 17 thus shortening the strut 50 14, 15.

Fig. 5 shows an intermediate position of the telescope spring 14, 15, where the spring 55 is held under some tension.

In order to lower the top, first the front members 10 are to be slightly lifted to be brought into the Figure 2 position. In this 60 position the said latch or support 26 normally swung down, is now to be turned up so as to engage under link 12 of the parallel link connection. This will prevent the members 10 from collapsing when the operator has turned his attention to the rear part of 65 the top. By pulling the strap 25 the opera-

tor is now enabled to completely fold the entire top structure.

Having thus described my invention, what I claim as new and desire to secure by Letters Patent, is:

Folding top structure for a vehicle having a windshield comprising columns pivotally connected to the body of the vehicle to fold thereon, cant rails each comprising a member hinged at one end to one of said columns and a second member hinged at one end to the free end of said first member and adapted to be secured at its other end to the windshield, telescoping members each hinged at one end to one of said columns and at the other end to one of said second cant rail members, a spring housed in one of said telescoping members tending to hold said members in extended relation, and means for limiting the relative 80 separating movement of said telescoping members whereby said members act as a tension member when in extended relation to support said second cant rail members.

In testimony whereof I affix my signature. 90
ALEXIS KELLNER.
